UNITED STATES PATENT OFFICE.

HOWARD C. DAVIS, OF ELIZABETH, NEW JERSEY, ASSIGNOR TO AMERICAN MARINE EQUIPMENT CORPORATION, A CORPORATION OF DELAWARE.

FEED-WATER HEATER, CONDENSER, AND THE LIKE.

1,400,347.

Specification of Letters Patent. Patented Dec. 13, 1921.

Application filed March 5, 1920. Serial No. 363,380.

To all whom it may concern:

Be it known that I, HOWARD C. DAVIS, a citizen of the United States, residing at Elizabeth, in the county of Union and State 5 of New Jersey, have invented certain new and useful Improvements in Feed-Water Heaters, Condensers, and the like, of which the following is a full, clear, and exact description.

10 This invention relates to feed-water heaters, condensers, and the like and more particularly to those in which the exchange of heat between two fluids is effected by means of coils or conduits through which 15 one fluid passes and around which the other fluid is conducted. In such devices, now in common use, the condensation around one coil tends to drip upon and coat another portion of the same coil or upon other coils 20 or contact surfaces disposed beneath it, and I have found that this coating of liquid condensation upon the coils tends to retard the interchange of heat between the coil or contact surface and the surrounding fluid, thus 25 very materially reducing the efficiency and capacity of such devices. My invention therefore has for one of its objects the provision of a construction whereby the dripping of the liquid condensation from one portion of the 30 contact surfaces upon other portions thereof will be reduced to a minimum.

Other objects and advantages will be apparent from the following description and the novel features of my invention will be 35 particularly pointed out in the claims.

In the drawings:

Figure 1 is a sectional elevation of one embodiment of my invention.

Fig. 2 is a sectional elevation of the same, 40 but with the section taken at right angles to that of Fig. 1.

Fig. 3 is a transverse sectional plan of the same, and

Fig. 4 is an elevation, showing a slightly 45 modified construction.

The main shell or casing 1 may be of any suitable shape, and has an opening in its side wall, providing access to its interior, which is normally covered by a door or 50 closure 2, removably attached thereto, such as by bolts 3. Upon each side of the closure and extending parallel therewith and lengthwise of the casing, are a plurality of headers or conduits 4, 5 and 6, which are preferably 55 cast integral with the casing. The

headers 4 and 6 may be in axial alinement, but are independent of each other. The casing is divided into a plurality of compartments or chambers by a series of partitions or baffle plates 7, which preferably 60 extend forwardly from the rear wall and alternately from opposite sides of the casing nearly across the interior thereof. Due to the fact that the baffle plates 7 extend from each side alternately nearly across the 65 casing each chamber or compartment communicates with the adjoining chambers by passages which are not in alinement and which are arranged in a staggered relation thereby forming a tortuous ascending passage through the casing. Each plate extends nearly to but is spaced from the closure, so that adjacent the closure is a direct 70 ascending passage for a purpose to be hereinafter explained. 75

Disposed within each chamber is a heat exchange or coil unit 8 which may be of any suitable construction, but preferably comprises a double coil of peculiar formation. It is made up of two sections, the convolutions of each section lying in the same plane with each other but in a plane parallel to those of the adjacent section. In forming the double coil, the pipe from which the same is produced is bent spirally 85 inward from its periphery to form one section, is then bent downwardly and laterally from a point adjacent the center of the section to the plane of the adjoining section, and is then bent spirally outward in 90 the same direction to the periphery to form the second section. The terminals 9 and 10 of the coil are thus located at the periphery thereof, and when the coil is in place in the casing 1, said terminals lie at points 95 adjacent the opposite side edges of the door or closure 2. The coil is thus very compact, all sharp bends are avoided, the terminals are at the periphery so as to be readily accessible, and the coil units are rendered 100 reversible, and interchangeable. Both sections of the coils are substantially parallel with the partition plates 7. One terminal 9 of each coil is removably connected to the header or conduit 5 by means of any suitable coupling 11. The other terminals 10 of part of the units are connected in a similar manner to the conduit or header 4, and the other terminals 10 of the remainder of the units are similarly connected to the con- 110

duit 6. Suitable valves 12 and 13, are arranged to supply a fluid through one conduit or header to the terminals 10 of one part or group of the coil units, the fluid 5 passing through this group of coils or units into the common header or conduit 5, thence into the other part or group of the coils through their terminals 9, and then by means of their terminals 10 into the other 10 conduit or header. A suitable conduit 14 and valve 15 are arranged to supply another fluid to one portion of the casing and this fluid is removed from the casing through a suitable outlet 16 in another portion of the 15 casing. Thus when the device is used as a feed water heater or condenser, the feed or cooling water would be supplied to header or conduit 6 by means of valve 13, from which it would pass through any or 20 all of the coils connected thereto into the common header 5, then through the other coils into the header or conduit 4, from which it is removed through valve 12. The steam or vapor to be condensed would be 25 admitted to the casing by means of conduit 14 and would pass through the staggered passages in the plates or partitions, and also through the direct longitudinal passage adjacent the door into all of the chambers 30 formed by the partitions. The staggered passages assist in the circulation and prevent pockets from being formed in the chambers, although other venting means could be employed, or these passages could 35 be omitted entirely. The condensed fluid which is produced by the interchange of heat between the two fluids, drops upon the partition beneath it and is conducted thereby to one of the staggered openings 40 therein through which it passes to the bottom of the next lower chamber, or it passes into the direct channel between the partition plates and the closure, through which the condensed fluid passes directly to the 45 bottom of the casing and does not drip successively from one coil unit to another to retard the interchange of heat between the two fluids due to the coating of the coils by the condensed fluid, which prevents the 50 vaporous fluid surrounding the coils from coming in contact with the coil surfaces. Only a small proportion of the condensed fluid will pass through the staggered passages since the major portion will pass to the 55 bottom of the casing by the direct passage-way which is adjacent the closure. If the coils project slightly beyond the partitions, as illustrated, a small area of each of the coils would be coated by the drippings of 60 the condensed fluid from the coils above it, but the major portion of each coil would not be affected thereby. Any suitable trap 65 may be connected to the outlet 16 in order to provide for the removal of the liquid condensation. The direction of flow through

the coils may be changed, if desired, by interchanging the supply pipes leading to the valves 12 and 13.

In Fig. 4 I have illustrated a slightly modified embodiment in which two headers 70 or conduits 17 extending lengthwise of the casing are used, and between which all the coil units are connected. The feed water or cooling fluid would enter through one of these headers, pass through the coils and 75 leave the apparatus by means of the other header.

While I have described my invention with reference to its use as a feed water heater, or a condenser, it is obviously not confined 80 to this use, and may be used as the medium for the interchange of heat between other and different fluids. Various other modifications may be made in the construction, as illustrated in the drawings and above particularly 85 described, within the principle and scope of my invention.

I claim:

1. In a device of the character described, a casing, a plurality of partitions in said 90 casing forming a plurality of chambers therein, said chambers being connected by aligned passages leading from one chamber to another throughout the length of the casing, and conduits in said casing and passing 95 through said chambers.

2. In a device of the character described, a casing having a removable side wall acting as a closure therefor, partitions in said 100 casing extending adjacent to but spaced from said closure, and forming within said casing a plurality of intercommunicating chambers, and conduits passing through said chambers.

3. In a device of the character described, 105 a casing, a plurality of partitions extending transversely of the casing to form within said casing a plurality of chambers, each chamber communicating with its adjacent chambers by aligned passages and also by 110 passages leading from opposite ends thereof, and conduits passing through said chambers.

4. In a device of the character described, a casing having a removable side wall acting as a closure therefor, transverse partitions within said casing extending forwardly from the rear wall and alternately from each side wall nearly across the casing, said partitions being adjacent to but 115 spaced from the closure whereby a passage extends lengthwise of the casing and communicates with each chamber formed by the partitions, and conduits passing through 120 said chambers.

5. In an apparatus of the character described, a casing having a removable side wall acting as a closure therefor, a plurality of coil units disposed within said casing, means for supplying a fluid to said coil 130

- units and for also removing it therefrom, partition plates disposed between adjacent coil units, and extending alternately from opposite sides of the casing nearly across 5 the same, each plate also extending forwardly from the rear wall and adjacent to but spaced from the closure, and means for supplying a fluid to said casing at one portion thereof and removing it therefrom at 10 another portion.
6. In an apparatus of the character described, a casing provided with a plurality of conduits on opposite sides thereof, means adapted to supply a fluid to one of said 15 conduits and means adapted to remove the fluid from another of said conduits, a plurality of coil units disposed within said casing, certain of said units connecting the conduit to which the fluid is adapted to be supplied with another of said conduits, and 20 certain of said units connecting the last mentioned conduit with the conduit from which the fluid is to be removed, plates disposed between the coil units, and means for supplying another fluid to the interior of 25 the casing at one portion thereof and for removing it therefrom at another portion.

In witness whereof I hereunto subscribe my signature.

HOWARD C. DAVIS.
